UNITED STATES PATENT OFFICE

2,247,001

LIQUID FUEL BURNER

Milton A. Powers, Detroit, Mich., assignor to The
Timken-Detroit Axle Company, Detroit, Mich.,
a corporation of Ohio

Application June 27, 1938, Serial No. 216,144

8 Claims. (Cl. 158—4)

The present invention relates to liquid fuel burners, and especially to fuel burners of the type where a fuel distributor is disposed substantially centrally of a hearth and designed to project the fuel substantially radially outwardly into surrounding parts of the combustion chamber. The invention is especially concerned with an improved wall tile designed to surround the fuel distributor adjacent the periphery of the hearth in or adjacent the region of combustion.

A ring of the general type improved upon by the present invention is shown in several patents of the prior art and in my Patent No. 2,130,471, dated September 20, 1938. However, my improvement finds greatest present value on the conversion type installations in oil burners and furnaces where it has been customary heretofore to install a row of refractory bricks or to form the wall from molded hearth material, as a backing wall over a portion or all of the periphery of the flame rim and located just outside of said flame rim.

The backing member formed by this wall is positioned radially outwardly from the fuel impingement wall and extends a few inches above the height of the flame rim itself. In this position the wall serves as a substitute for the actual heat absorbing walls or combustion chamber of the boiler or furnace. Consequently, it serves several useful and important functions—not all of which may be described on any particular installation. One of the most important functions is to maintain normal combustion conditions over the length of the flame rim, backed by such member. This is best explained where, for example, the flame rim is positioned at varying distances from the heat absorbing walls as frequently occurs on a long rectangular hearth where the flame rim occupies but a portion of the total periphery of the combustion chamber. In such cases very poor combustion will be obtained if no backing member is used. Reference to my Patent No. 2,065,393, issued December 22, 1936, and the discussion therein on combustion of the wall flame burner emphasizes the part played by a wall member in proximity to the flame rim of a wall flame burner.

Another important function, particularly on warm air furnaces, is to prevent the intense heat of the flame from directly impinging against the metal wall which, it can be readily understood, materially accelerates its deterioration. In such a case it has been the general practice to install a backing member of clay refractory

brick about the entire inner periphery of the furnace wall, although the tile of this type have at various times caused a number of troubles which will be discussed later.

5 A ring made of clay refractory brick or tile is heavy, relatively expensive, of relatively short life, and is open to the further objection that it has sufficient porosity to absorb oil or oil vapors, and absorbs large amounts of heat during the operation of the burner, which heat radiates back and has destructive effects on the burner during the periods in which it is not operating.

It is, accordingly, the primary object of the present invention to devise an improved metal ring formed of a multiplicity of flexibly interlocked segments, thus improving on the earlier types of rings while maintaining any and all advantages that were present in said earlier rings. The multi-segment ring of this invention is easier to handle and more compactly bundled for shipment than either brick or a one-piece ring. It is cheaper and lighter than brick, and more flexible than a continuous strip steel ring. The flexibility of my improved ring also eliminates any warping, distortion or slipping of the ring in use and facilitates installation.

Specifically then, it is a major object of my invention to devise a multiple segment ring in which the segments may be readily and flexibly joined or interlocked, either at the factory as part of a complete apparatus or "on the job" for modernization purposes.

It is a further object of the present invention to devise a multi-segment metal ring having flexible joints which permit automatic vertical adjustments of the individual segments. In this connection it is also an object to permit a limited amount of flexibility or adjustment circumferentially and radially of the ring to allow thermally induced expansion and contraction to freely take place without throwing the wall out of proper alignment and without distorting the parts thereof.

The vertical wall flame burner requires a generally circular flame ring for proper operation because the oil and air are thrown toward the flame ring by a centrally located distributor head. Although the flame ring assembly may be of elongated or elliptical form, it has been found that in rectangular furnaces which are being converted into rotary wall flame furnaces it is impractical to make the flame ring assembly exactly conform to the rectangular walls.

In installations of this character spaces are 55 left behind the flame ring assembly which must

be blocked off to prevent the oil and air from being blown off into those spaces and incorrectly mixing. Heretofore, it has been the practise to block off such spaces with refractory clay segments and although they effect proper mixing of the fuel and air, they are not completely satisfactory because they do not fit the combustion chamber exactly, requiring filling in with clay, they are heated to an excessive temperature and often crumble away, and they cool slowly, giving 10 rise to pre-ignition difficulties.

It is quite apparent that the use of my metallic wall structure in place of the heretofore conventional masses of clay brick and molded refractory will result in a hearth construction of much less weight and consequently greatly reduced heat absorbing ability. In other words, a hearth of my improved construction heats and cools very much more rapidly. This produces much higher combustion efficiency earlier in starting as but little heat is absorbed by the backing structure and it quickly reaches maximum temperature. Furthermore, and probably of even greater importance, particularly in direct fired warm air installations, much better room temperature control is possible in addition to improved burning efficiency.

On direct fired installations, there has been a marked tendency in specifying equipment to provide a heating plant with relatively little excess burning capacity above the maximum heat requirements of the building. This is due to the fact that the rapid response of a forced warm air system will cause too rapid a rise in room temperature, following which the room thermostat is satisfied and considerable time may elapse before the next call is made for heat—resulting in a noticeable unevenness in temperature throughout the building. This undesirable condition is further accentuated by the “flywheel” effect of the heat stored in the refractory in the combustion chamber, which slows down the heat delivery to the rooms at the start of the heating period due to heat being absorbed by the refractory. When the thermostat is satisfied, the hot mass gives up its heat, resulting in an overrun in room temperature which is highly undesirable.

With my light weight structure, this characteristic is eliminated and the desired room temperature exactly obtained in the shortest time with maximum burning efficiency during the entire period.

It is, accordingly, a further object of this invention to provide a metallic wall structure for blocking off spaces in furnaces embodying rotary wall flame burners which are of simple design, will last indefinitely without having its efficiency impaired, and which will heat up and cool rapidly, thereby obviating pre-ignition difficulties.

It is another object of my invention to devise metal ring segments of generally cylindrical curvature which may be used in varying numbers within a given range to produce rings of different diameters and shapes.

It is a further object of this invention to provide a joint for ring segments or the like comprising cooperating tabs and slots, the slots being wider than the tabs and the tabs having lateral indentations which facilitate bending them after insertion through the slots, and which also locate the bending lines so that the segments will be properly disposed relative to each other.

A further object is to devise a backing wall assembly for a wall flame burner having an oblong shaped flame wall which is designed to materially improve combustion conditions therein.

The foregoing and further objects of the present invention will become more clearly apparent from a consideration of the following detailed description taken in conjunction with the accompanying drawings and the appended claims.

In the drawings:

Figure 1 is a vertical sectional view through the bottom part of a furnace having the improved liquid fuel burning apparatus of the present invention mounted in its combustion chamber, substantially as it would be seen by looking upon the line 1—1 in the direction of the arrows of Figure 2;

Figure 2 is a horizontal sectional view through the apparatus of Figure 1 and shows the distributor mechanism and the various walls mounted on the hearth in top plan view;

Figure 3 is a face view of one of the multiplicity of segments used to form the backing walls illustrated in Figures 1 and 2, the tabs on the segments being shown in their initial or manufactured position prior to bending;

Figure 4 is a view illustrating the manner of joining a pair of the segments of Figure 3, the tabs in this assembly having been bent to a position to flexibly interlock the segments;

Figure 5 is a sectional view taken through one of the interlocking joints of Figure 4 as seen when viewed on line 5—5 in the direction of the arrows;

Figure 6 is a vertical sectional view on an enlarged scale of one of the flame ring segments and shows how it cooperates with the backing wall;

Figure 7 is a top plan diagrammatic view somewhat similar to Figure 2 but shows a modified form of backing wall assembly; and

Figure 8 is a fragmental elevational view of one of the backing wall plates used in the device of Figure 7.

With continued reference to the drawings and with particular reference to Figures 1 and 2, the reference numeral 8 designates a base forming a compartment and having an upper inturned flange 9 which supports the hollow boiler section 10. A horizontally disposed ceramic hearth assembly indicated generally at 12 is molded in place on a metal plate assembly 13 which is supported by flange 9. Plate assembly 13 is also supported in part by the distributor mechanism, to be presently described.

The distributor mechanism is indicated generally at 17 and is disposed centrally of the apparatus. The hearth assembly is centrally apertured to permit installation of the distributor and to also allow the entrance of fuel and air into the combustion chamber, the fuel being thrown in solid droplets substantially radially outwardly by a pair of tubes 18, which rotate in fixed relation to and with a fan structure 19, the latter being designed in well known manner to spread a sheet of air outwardly over the hearth surface toward its periphery.

A plurality of heat resistant metal segments 20, each having a sloping wall 21 and an upright wall 22, are disposed upon the upper hearth surface substantially in concentricity with the surrounding combustion chamber wall. Surface 21 deflects the outwardly thrown stream of air upwardly towards the top of the wall 22. Segments 20 are preferably formed of a sheet metal that has good conductivity and has high resistance to destruction by heat. In operation, the upper portion of wall 22 is impinged by the droplets of oil thrown outwardly from tubes 18. Segments 20 are preferably supported upon brackets 23 which

have prongs embedded in the hearth while the latter is still plastic.

The specific construction of the distributing mechanism and these brackets is described and claimed in my Patent No. 2,065,393, granted December 22, 1936. The mixture of fuel and air is preferably ignited through electric means, for instance, a pair of electrodes 24 operating to establish electric arcs between them and ring 22. As the ignitor mechanism is also shown in my aforesaid prior patent, and as no claim is made thereto herein, they will not be further shown nor described.

After ignition has taken place, a hot flame is propagated at the top of the wall 22, some of the flame passing upwardly and then downwardly outside of wall 22 to cooperate in direct heat-transmitting relationship with the inner walls of the boiler sections.

The apparatus thus far described corresponds with that disclosed in my aforementioned patents, and the apparatus of my invention which makes it possible to mount a wall flame burner, which normally requires a circular or elliptical flame wall, in a rectangular or oblong boiler, will now be described.

Referring to Figures 1 and 2, a large "dead space" is located in the rear of the furnace and two smaller spaces appear at the front of the furnace between the furnace wall and the flame ring segments. These dead spaces are "blocked off" as follows:

Disposed outwardly of segments 20, and disposed in substantially parallel spaced relationship thereto, both at the front and rear of the boiler, is a backing wall 25 composed of a multiplicity of identical steel segments 26, the segments being flexibly secured together in a manner yet to be described to present, in effect, a continuous surface outwardly of segments 20 at 40 opposite ends of the boiler. Backing wall 25 is considerably higher than segments 20, approximately twice as high in the illustration, but the height may be varied as is found suitable, depending upon the factors of the particular installation at hand. Backing wall 25 may be secured to the hearth by means of a plurality of brackets (not shown) having prongs embedded in the hearth and a pair of upstanding fingers between which the individual elements of the backing wall may 50 seat. In the drawings, however, I have illustrated the backing wall as seating snugly against the hearth surface and supporting brackets 23 as being provided with fingers 27 which abut the inner surface of backing wall 25 and maintain it in proper spaced relation to the flame ring. If desired, however, elements 26 may be partially embedded in the hearth.

Both of the backing walls 25 terminate at each end adjacent the boiler wall, where the latter is of flat configuration, and are located close to ring 22. In other words, walls 25 are only used in that part of the chamber wherein the boiler wall is spaced considerably from segments 20 and would otherwise allow the products of combustion to eddy out into the large "dead" spaces and be improperly combusted. Walls 25 also incidentally function to prevent oil from "splattering" or splashing and thereafter accumulating remote from the flame ring where it would be difficult to vaporize, and it also cooperates with the back of the impingement wall 22 to form a reverberatory chamber for the downwardly swirling flames and gasses of combustion, thus main-

taining the efficiency of heat transmission at the highest possible maximum.

If it were not for the fact that, in the conversion installation illustrated, a clinker "clean-out" door 28 is located at the front of the boiler, and which is filled with refractory cement so as to constitute a "dead" wall, the backing wall for the front of the furnace could be made in two parts, so as to merely "block off" the two corners and allow the flame to cooperate directly with the front wall of the furnace.

The segments 26 of the backing wall are formed of very thin sheet metal, such as chromium steel, that is highly resistant to distortion or destruction by heat and that does not easily bend out of shape in handling. The thickness is exaggerated in the drawings for clarity of illustration. The segments thus are very light in weight and, being of uniform rectangular size may be packed nicely for shipment and for ease of handling. An important feature of the present invention resides in the means for flexibly interlocking the segments to form the complete ring. This feature will now be described in detail, with reference particularly to Figures 3, 4 and 5.

Each plate or segment is of substantially cylindrical curvature and its height preferably is considerably greater than its width. Along one of its vertical edges it has two or more (three in the illustrated form) rectangular fastening elements 29 which are horizontally disposed and properly spaced with respect to one another vertically along the edge. Each element 29 is formed of very thin metal having substantially the same characteristics as the metal of the segments 26, and it is arranged with one of its ends in surface contact with the segment, to which it preferably is secured by spot welding as indicated at 30. The other end of the fastening element thus projects horizontally beyond the edge of the segment to form a tab 32. Horizontally aligned with this tab and disposed in the opposite vertical edge of the segment is a slot 33 which is cut vertically and which is considerably wider than the tab thickness and considerably longer than the tab width. The number of slots, of course, corresponds with the number of tabs on each segment.

The tabs at the edge of one segment are readily inserted, just as they appear in Figure 3, through the slots of another segment by disposing the two segments at a slight angle to each other and bringing their edges that are to be joined into overlapping relationship. The angle of disposition for performing this manipulation may be very small due to the fact that the tabs pass freely through the slots as a result of the slot dimensions being considerably greater than those of the tabs.

Each tab is provided, adjacent the edge of the segment to which it is secured, with a pair of vertically aligned notches 34, these notches being located in the upper and lower edges of the tab. After the tabs have been inserted in the slots in the manner set forth in the preceding paragraph, they may be readily bent into the position shown in Figure 4 by applying force laterally to their outer ends. This step is easily performed as a result of localized weakness produced by the notches 34. These notches 34 not only facilitate the bending operation, but they also definitely and accurately locate the vertical "line of bend" so that the joints between each pair of segments will properly position the matched edges of the latter to bring one into

slightly overlapping relation on the other and afford, in effect, a continuous cylindrical surface through which the fuel cannot escape in a direction radially of the hearth.

The width of each tab, between the bottoms of its pair of notches, is only about half the width of the slot in which it is confined, and thus each segment has considerable vertical play with respect to the others of the ring or backing wall. Each segment also has a circumferential play as a result of the width of the slot being greater than the thickness of the tab which it receives. In addition, the notches are sufficiently wide in a horizontal direction to permit each segment to have a slight radial play with respect to the axis of the ring.

The series of joints thus formed are very flexible and permit automatic adjustment of the segments relative to each other in all directions. As a result the entire ring will seat itself fully upon the hearth, and should any segment have a tendency to distort into changed shape as a result of high and varying temperatures, there will be little or no tendency for the entire ring to warp or pull out of place. The life of the backing rings is, therefore, equal to or greater than that of the rest of the oil burning apparatus.

As seen in Figure 6, brackets 23 are secured to supports 23a as by welding or the like and fingers 27 are formed as a part of the support and are of the requisite length to properly space segments 26 from segments 20, and if desired, they may be welded or otherwise secured thereto, so as to more firmly anchor the parts together. Brackets 23 are provided with tabs which are bent over to clamp segments 26 in place as seen more clearly in Figure 6.

The advantages of the metal backing wall over the refractory clay segments heretofore used are many. The ease of installation is apparent, the segments being selected in proper number to just exactly fill the space involved and may be arranged to assume any desired shape of wall.

Also, the metal segments, being thin and highly conductive, heat up and cool down rapidly, thereby eliminating preignition difficulties, thereby allowing the burner to be restarted shortly after being shut down. The metallic segments, moreover, will not burn out or "crumble" as clay refractories have done in the past.

In some installations a set of metal grills of the type shown in my aforesaid Patent No. 2,065,393 and which are of a type now well known, may be mounted on the upper edge of segments 20 to shorten the flame of combustion.

Also, I have shown my invention incorporated in an apparatus having a ceramic hearth but it is to be understood that if desired it may be mounted in a furnace having a metal hearth, and in that case both segments 20 and 26 may be welded or otherwise suitably secured thereto. Also, the invention may be employed in combustion chambers having other than a rectangular cross section if desired.

For instance, in combustion chambers which are substantially square in horizontal section, the backing wall of my invention may be utilized to block off the corner spaces. Also, I have shown a fuel burning apparatus embodying segments 20, but it is to be understood that the backing ring of the invention may be used with apparatus embodying two concentric upstanding rings which provide both an air deflecting

wall and an impingement wall such as is shown in my Patent No. 2,107,800, dated February 8, 1938, and they may be disposed so as to define a truly circular flame ring assembly or may define an elliptical assembly.

From the foregoing, it is apparent that I have provided a novel and efficient apparatus for combusting liquid fuel and it is, moreover, ideally adapted to the conversion of rectangular or other odd-shaped coal burning furnaces into wall flame burners since the installation of the backing wall is readily effected by selecting the proper number of metal segments required to fill the "dead spaces" and putting them in place on the hearth, thereby obviating the need for cutting or shaping the parts or using clay or other ceramic material to fill in gaps between the backing wall and the boiler sections.

The novel backing wall of the invention may be used in other relationships in liquid fuel burning apparatus of the general type illustrated and in other types where a heat-resistant, light flexible ring is desired or needed.

In Figure 7 I have somewhat diagrammatically illustrated the parts shown in Figure 2 as cooperating with a modified form of backing wall which is shown more clearly in Figure 8.

It has been discovered that in some wall flame burner installations where the flame wall is of oblong shape, the flame will tend to "creep" into the regions designated as "A" in Figure 7. This is a distinct disadvantage because the flame is divided in two parts and inefficient combustion and heat transmission results. I have found that by providing perforated backing plates 26a in the two regions designated "B," the flame is held in those regions and does not "creep" around and concentrate itself in the regions "A." One of the plates 26a is illustrated in Figure 8 and it is provided with a plurality of apertures 36 through which the flame may eddy and mix, thereby improving the character of the flame. If desired, all of the plates 26 may be perforated as shown in Figure 8.

The invention may be embodied in other specific forms without departing from the spirit or essential characteristics thereof. The present embodiments are, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed and desired to be secured by United States Letters Patent is:

1. In a liquid fuel burning apparatus, a combustion chamber closed by a hearth, fuel projecting means at the center of said hearth, a fuel intercepting wall disposed outwardly from its center, a backing wall of greater height than said fuel intercepting wall and spaced outwardly therefrom in proximity to the hearth periphery, said backing wall comprising a multiplicity of upright thin sheet steel segments, each being of substantially cylindrical curvature and slightly overlapped on another, and means for retaining said segments in their upright overlapped relationship.

2. A liquid fuel burning apparatus comprising a hearth, fuel supply means located centrally of and above said hearth and designed to project liquid fuel toward the hearth periphery, a refractory ring located inwardly from the hearth

periphery, and providing a fuel impingement wall facing inwardly toward the fuel supply means, and a backing wall adjacent the hearth periphery in parallelism with said refractory ring, said ring being materially spaced from said backing wall upon the hearth surface and the backing wall being materially higher than the refractory ring, said backing wall comprising a flexibly interconnected series of thin segmental plates of a material resistant to destruction by heat.

3. In the apparatus defined in claim 2, means for feeding air against said impingement wall in a manner to cause the flame of combustion to swirl downwardly into the space between said refractory ring and said backing wall, said wall and said refractory ring both being of metal of good heat conductivity, and the surfaces of said plates being smooth and mirror-like.

4. In the combination defined in claim 2, said plates being interconnected by joints that are slightly flexible vertically, circumferentially and radially, whereby a change in shape in one of the plates will not warp the entire backing ring or move any portion thereof out of contact with the hearth.

5. The combination defined in claim 2, with refractory bridge elements extending between

said backing wall and said refractory ring for maintaining the same in accurately spaced relationship.

6. In a liquid fuel burning apparatus, a combustion chamber of generally rectangular shape in plan, a hearth structure mounted in said chamber, a centrally located distributor for throwing a blast of oil and air outwardly over said hearth, a flame ring assembly cooperating with said distributor and mounted on said hearth and being of generally curved form, said flame ring assembly lying in close proximity to the walls of said chamber but being curved at the corners of the latter, and an upright metallic wall structure disposed between said flame ring structure and the walls of said chamber for preventing said oil and air blast from blowing into said corners of said chamber.

7. The liquid fuel burning apparatus described in claim 6, wherein said metallic wall is made up of a plurality of articulated segments.

8. The liquid fuel burning apparatus defined in claim 6, wherein at least a portion of said metallic wall structure is perforated, for preventing the flame from localizing itself in certain regions of said combustion chamber.

MILTON A. POWERS.
